United States Patent Office

Des. 202,703
Patented Nov. 2, 1965

202,703

PRINTER CONSOLE

Rovert V. Mallory and Edward J. Sabella, both of Vestal,
N.Y., assignors to International Business Machines
Corporation, New York, N.Y., a corporation of New
York

Filed Sept. 28, 1964, Ser. No. 81,885

Term of patent 14 years

(Cl. D26—5)

FIG. 1

Des. 202,703

PAGE 2

FIG. 2

FIG. 3

FIG. 4

FIG. 6

FIG. 5

FIG. 1 is a front perspective view of a printer console embodying our new design.

FIG. 2 is a rear elevational view.

FIG. 3 is a left-side elevational view.

FIG. 4 is a right-side elevational view.

FIG. 5 is a front elevational view.

FIG. 6 is a top plan view.
The essential features of our design reside in the portions shown in solid lines in the drawings.

We claim:

The ornamental design for a printer console, as shown and described.
